UNITED STATES PATENT OFFICE.

JAMES D. O'DONOGHUE, OF BROOKLYN, NEW YORK.

TOY RACE-COURSE.

SPECIFICATION forming part of Letters Patent No. 288,476, dated November 13, 1883.

Application filed October 1, 1883. (No model.)

To all whom it may concern:

Be it known that I, JAMES D. O'DONOGHUE, of Brooklyn, in the county of Kings and State of New York, have invented a Toy Race-Course, 5 of which the following is a specification.

This toy contains figures of horses, men, or other animals carried around in a circle upon independent arms, and a ball rolling down a circular inclined track is employed to give motion to the figures, and the devices against which the ball acts are so constructed that there is no certain amount of motion given to such figures, and it is a matter of chance which may arrive first at the end of the race. This toy 15 affords considerable amusement, especially to children.

In the drawings, Figure 1 is an elevation, partially in section, showing the construction of the toy; and Fig. 2 is a plan view.

20 There is a base, *a*, supported upon suitable feet, *b*, and a circular platform, *c*, connected with the base *a* by the bows or arches *d*, through which the figures are moved around above the circular track formed by the slot between the 25 outer edge of platform *c* and the inner edge of the base *a*.

There is a cross-bar, *e*, beneath the base *a*, firmly connected with the said base, upon which cross-bar is a vertical axis or pivot, *f*, that 30 passes up to the top of the circular inclined track, and it is securely fastened at the bottom to the cross-bar. Around this vertical axis *f* there is a fixed open spiral or helical wire, *g*, the ends of which are fastened to such axis, and around outside thereof there is a 35 second helix or open spiral wire, *h*, having the same number of convolutions, but of considerably larger diameter. These two helices form a circular inclined track down which the ball 40 *l*, of metal or other heavy material, can roll. The helix *h* is fastened at the lower end to the platform *c*, and at the upper end to the disk *m*, which has a central hole for the passage of the axis *f*, and a gallery, *n*, around the outside. This gallery may be at the upper end of a cylindrical or other shaped case or tower 45 in the center of the platform *c*, to inclose the helical wires forming the cylindrical inclined track; and I remark that there is an opening

in the disk *m*, through which the ball *l* is introduced to run down the tracks formed by the helices.

There are two, three, or more figures, *P*, of horses, men, bicycles, or other devices, and these are supported at the ends of arms *r*, *s*, *t*, 55 each of which arms has an eye surrounding the axis *f*, and a vertical bar, *r'*, *s'*, or *t'*, with an arm at the upper end, having an eye around the upper part of the vertical pivot. The arm *r* is the longest and lowest, and the arm *t* the 60 shortest and highest, so that the respective figures will swing clear of each other, the figure on the arm *s* swinging between the other two arms. So, also, the vertical bar *s'* is between the bars *r'* and *t'*, and the arm and parts are arranged, 65 as shown, so that the figures may move one ahead of the other and be free to describe almost a complete circle. Upon the respective vertical bars *r'*, *s'*, *t'* there are projections, preferably in the form of bends or zigzags in the 70 wires. These may be more or less irregular. The wires or bars *r'*, *s'*, *t'*, being between the spirals or helices *g* and *h*, are acted upon by the ball *l* as it rolls down the inclined plane formed by such helices; hence when in use 75 this ball gives to the horses or other toy figures a movement which generally becomes augmented, and the ball sometimes striking an incline or zigzag projection of the bar causes the horse with which it is connected to forge ahead; 80 hence the toy racer that comes in first is always a matter of uncertainty.

The parts may be connected together by screws, so that they may be detached for packing.

85 The judge's stand is represented at *v*, and I place a bell, *w*, beneath the platform in a position where the ball, as it emerges from the helices, falls against the bell and gives a signal of the race being finished. A trough or 90 receptacle, *w'*, may be provided to receive the descending ball, after it has struck the bell, and prevent it rolling away.

If the vertical bars *r'*, *s'*, *t'* were straight, there might be a nearly uniform movement of all 95 the toy horses as the ball runs down in contact with such bars; but by introducing the zigzags into such wires the movements are ac-

celerated and the period of rotation changed, so that there is no positive relative movement of the toy horses, and it cannot be reliably told which will reach the end of the race the first.

5 I claim as my invention—

1. The combination, in a toy race-course, of two helices, a vertical pivot, arms with figures, vertical bars connected with the arms, and a ball acting to give motion to the parts 10 as it runs down such incline, substantially as set forth.

2. The base *a*, circular platform *c*, and connecting-arches *d*, in combination with the vertical axis, the helical tracks, the toy figures, 15 the arms carrying the same, and vertical bars

connected with the arms and against which the ball acts, substantially as set forth.

3. The combination, with the helical track and ball, of the vertical axis, the toy figures, the arms connecting the toy figures, and the 20 vertical bars, with projections or zigzags for the ball to act against, substantially as set forth.

Signed by me this 27th day of September, A. D. 1883.

JAMES D. O'DONOGHUE.
